UNITED STATES PATENT OFFICE.

WILLIAM BINGHAM OWEN, OF DETROIT, MICHIGAN.

ADVERTISING DEVICE.

No. 845,704.

Specification of Letters Patent.

Patented Feb. 26, 1907.

Application filed November 25, 1905. Serial No. 289,086.

To all whom it may concern:

Be it known that I, WILLIAM BINGHAM OWEN, a citizen of the United States of America, residing at Detroit, in the county of Wayne and State of Michigan, have invented certain new and useful Improvements in Advertising Devices, of which the following is a specification, reference being had thereto to the accompanying drawings.

10 The invention relates to advertising devices especially designed for use in connection with moving vehicles, particularly street or steam railway cars, and consists in the novel construction of a traveling device of 15 the character referred to which moves automatically upon the starting and stopping of the vehicle and upon changes in speed, as will be hereinafter set forth.

In the drawings illustrating my invention, 20 Figure 1 is a view in front elevation of an advertising device embodying my invention. Fig. 2 is a fragmentary perspective view illustrating the construction of the traveling carrier. Fig. 3 is a view in front elevation of a 25 modified form of advertising device. Fig. 4 is a similar view of another modification. Fig. 5 is a section taken on line $\alpha-\alpha$ of Fig. 4. Fig. 6 is a section through a modification. Fig. 7 is a perspective view of the means of 30 attachment for the advertising device. Fig. 8 is a detached perspective view of the casing-cap, and Fig. 9 is a modified form of the construction illustrated in Fig. 1. Figs. 10 and 11 are central longitudinal sections, horizontal and vertical, respectively, of the construction shown in Fig. 4. Fig. 12 is a perspective view of a portion of a car, showing 35 the application of the device.

In Fig. 1 I have shown the device as consisting of an elongated casing, preferably a metallic open-ended tube, adapted to be arranged in the advertising-space on the side of the car near the top or ceiling in the manner hereinafter to be described. The casing in 40 this instance is provided with end caps A' A'' and, being detachable, is slotted longitudinally at the bottom, and within the casing is arranged a traveling member adapted to move to and fro from end to end of the casing automatically upon the stopping and starting of the car or a variation in speed. In the figure referred to two traveling members are shown, one (designated by the reference-letter C) in the form of a carrier and the 45 other (represented by the letter D) a ball or sphere. In the event that the ball only is to

be used the casing is usually formed of glass, as indicated at E, Fig. 3, the sphere D serving upon its travel to and fro merely to attract attention to the advertising matter arranged in connection with the casing, or, if desired, a plurality of balls or spheres, as indicated in Fig. 3, may be used for the same purpose.

In Fig. 1 the traveling carrier is in the form of an open-centered frame, which is provided with shoulders c^2 , engaging the inner surface of the casing at the sides of the slot F, and a depending extension C', projecting through the slot F in the casing-bottom and carrying a panel G, on which suitable advertising matter may be placed, the panel moving longitudinally of the car automatically in the manner previously set forth. Preferably the carrier is made of a light frame 75 which permits it to be manufactured at slight cost, and a sphere or ball, as D, is arranged within the frame, serving to operate the latter within the casing. The supporting means for the advertising device described comprises bands or straps, preferably of spring metal, (indicated by the reference-letter H,) adopted to be inserted in the advertising-space of the car in the usual manner between suitable longitudinal strips, (not herein shown,) clips, or hooks 1 upon these separated bands, and extensions J, preferably in the form of flat tongue-shaped members arranged upon the casing ends and engaging the clip, as indicated in Fig. 7. The 80 means of attachment described is simple, inexpensive, and permits of the ready removal or replacement of the advertising novelty when desired.

In the modification illustrated in Fig. 9 95 the parts are of the same construction as previously described, with the exception of the traveling carrier-frame. This (indicated by the reference-letter K) is elongated sufficiently to permit of a limited independent 100 rolling movement of the sphere D, the result being that as the car stops or starts the ball will move immediately; but the panel G will remain stationary for a short period thereafter until the ball strikes the end of its 105 frame, when both move longitudinally within the casing, the desired traveling movement of the panel commencing unexpectedly after the car has stopped or started.

In Figs. 4, 5, 10, and 11 another modification of the device is shown, the casing, in this instance represented by the letter L, being

rectangular and provided with a panel M, which forms a part of the front of the casing and is adapted to have printed or arranged thereon the advertising matter. This casing 5 is provided with a rectangular cap O at one end, provided in turn with the extension J, as previously described, and with a similar cap member P at the opposite end, detachable, as in the other construction, to permit 10 of the insertion of the traveling member or members. The cap P is also provided with the hook Q, which engages the back plate R of the casing when the parts are assembled and prevents the latter from moving outwardly and out of engagement with the cap. The detailed construction of the carrier comprises a pair of vertical members a, each carrying a pair of oppositely-turned hooks b, that engage the edges e of the casing-front, 15 as plainly indicated in Fig. 5. These members described are connected by and carry the panel M, previously referred to. The members a also are provided with end pieces e, between which a circular weight or disk f 20 is adapted to travel, the weight having a relative independent longitudinal movement and serving as the sphere in the construction shown in Fig. 9 to operate the carrier. The members a are secured to the panel M by 25 solder or by any other suitable means.

In each of the constructions of casing shown pads, as S, preferably of felt, are arranged in the casing ends or caps and serve as yielding abutments for the traveling carrier 30 and also to deaden or lessen the noise of contact between the parts.

In Fig. 1 one of the caps upon the casing ends is fixed so that the slot will always be retained at the bottom of the casing and friction 35 between the latter and the traveling member thus reduced to a minimum.

The modification illustrated in Fig. 6 shows another and simpler connection between the panel M and the casing. Here the 40 panel is arranged and adapted to travel between pairs of fixed guides a' a' and b' b' upon the casing top and bottom, the device being otherwise of the construction shown in Fig. 5.

50 What I claim as my invention is—

1. In an advertising device for use in moving vehicles, the combination with a casing, closed at one end and having a detachable

closure for the opposite end, a traveling member within the casing, flat extension members 55 carried by the casing ends, and clips adapted to be secured to the car with which the extensions detachably engage.

2. The combination with a car, a pair of spaced bands or straps secured thereto, a clip 60 carried by each strap, a casing, a traveling member within the casing, and end extensions upon said casing detachably engaging the band-clips.

3. In an advertising device for use in moving 65 vehicles, the combination with an inclosing casing and means for securing said casing to the vehicle, of a carrier mounted therein for horizontal reciprocation and an operating member also within the casing having a limited independent movement for causing the delayed reciprocation of the carrier.

4. In an advertising device for use in moving vehicles, the combination with an inclosing 70 casing and means for securing said casing to the vehicle, of a carrier mounted therein for horizontal reciprocation, and means in the form of a rolling member for operating the carrier, said member being in operative relation to but having a limited movement 75 independent of the carrier for delaying the movement thereof.

5. In an advertising device for use in moving vehicles, the combination with an inclosing 80 casing and means for securing said casing to the vehicle, of a carrier-frame mounted therein for horizontal reciprocation, and a rolling member within and having a limited movement independent of said frame for causing 85 a delayed movement of the said frame. 90

6. In an advertising device for use in moving vehicles, the combination with a slotted inclosing casing and means for securing said casing to the vehicle, of an elongated open-centered carrier-frame mounted therein and projecting through said slot for longitudinal 95 reciprocation, and a rolling member arranged within the frame for limited independent horizontal travel.

In testimony whereof I affix my signature 100 in presence of two witnesses.

WILLIAM BINGHAM OWEN.
